FRANK S. ALIANO, OF BROOKLYN, NEW YORK.

SAFETY APPLIANCE FOR HAND-FED POWER-PRESSES.

1,246,834.

Specification of Letters Patent. Patented Nov. 20, 1917.

Application filed September 2, 1916. Serial No. 118,159.

To all whom it may concern:

Be it known that I, FRANK S. ALIANO, a citizen of the United States, residing at the borough of Brooklyn, city of New York, county of Kings, and State of New York, have invented certain new and useful Improvements in Safety Appliances for Hand-Fed Power-Presses, of which the following is a specification, reference being had thereto in to the accompanying drawings, which form a part thereof.

My invention relates to safety appliances for hand fed power presses and more particularly to improvements in the type of appliances patented to me under date of July 1, 1913, Letters Patent No. 1,066,459, wherein an oscillatory guard plate positioned between the die and the operator is moved upwardly and toward the operator with each actuation of the trip mechanism for the controlling clutch or by a lever system operated from the shaft actuating the ram.

In a safety appliance made in accordance with my invention, I so construct the actuating mechanism for the guard plate, that the power for setting the said guard plate, whether applied manually or through an emergency mechanism actuated from the power shaft, is transmitted through the same mechanism, thus not only simplifying the structure and installation of the appliance but insuring greater reliability in its mode of operation.

To secure other and further advantages, the guard plate is connected with, and actuated by a member having two sections, one of which is operative solely by the emergency actuating mechanism under the control of the ram shaft and the other of which is operative solely by the clutch tripping mechanism. In this manner, I am enabled to prevent the movement of the pedal, with its possibility of injury to the operator, when the guard is operated from the ram shaft, as in the case of the failure of the clutch or other disarrangement of the controlling means for said ram shaft.

In addition to this, the operator is prevented from tripping the press by raising the guard plate by hand, since the section of the actuating member connected with the pedal may transmit power to raise the guard, but is incapable of transmitting

power from the guard to the clutch mechanism.

The energy for restoring the guard plate to normal after each actuation thereof by the pedal mechanism, is the pedal spring but the capability of the emergency mechanism to operate the guard entirely independently of the pedal necessitates the use of an independent source of energy to restore the guard to normal after each actuation thereof by said emergency mechanism.

While guards of the character herein referred to, are designed primarily to protect the hands of the operator, it is not uncommon for operators, after a guard has been installed on a press, to so set the guard that it will not operate as intended, and to operate the press under the same conditions as though no guard had been applied thereto. In the type of machine referred to in my aforesaid Letters Patent, operators sometimes would completely reverse the guard plate, thus preventing its actuation by the foot pedal and at the same time, making the emergency mechanism inoperative. By using two independently operative sections controlling the guard plate, and providing means limiting the movement of that section operatively connected with said plate to that required to properly actuate the plate, it is impossible for the operator to follow the practice above referred to.

In addition to the foregoing characteristics, a guard made in accordance with my invention is designed to force the hand or hands of the operator from below the punch or ram prior to the release of the clutch controlling the power shaft of the machine, and to cause the repeated actuation of the guard in synchronism with the movements of the ram, in the event that the clutch be continuously inoperative to intermittently arrest the ram, either under the control of the operator, or because of accident.

A further characteristic of the invention is a particular form of support for the trunnions of the guard plate, by means of which the attachment of the guard, and its adjustment in relation to the bolster is facilitated.

The invention consists primarily in a safety appliance for hand fed power presses embodying therein a guard plate normally extending across and below the feeding

space between the punch and the operator, and actuating means therefor comprising a main actuating lever having three diverging arms, an emergency actuating mechanism 5 consisting of a cam carried by the power shaft of a press, and a cam lever coöperating therewith, and connections between one arm of said main actuating lever and said cam lever; between another arm of said main actuating lever, and the clutch tripping mechanism of a press, and between the remaining arm of said main actuating lever and said guard plate; and in such other 10 novel features of construction and combination of parts as are hereinafter set forth and described and more particularly pointed out in the claims hereto appended.

Referring to the drawings:—

Figure 1 is a perspective view of a punch 20 press having an appliance made in accordance with my invention applied thereto;

Fig. 2 is a perspective view of the main actuating mechanism with portions of the different connections for receiving and 25 transmitting power with relation thereto;

Fig. 3 is a rear elevation of the main actuating mechanism; and

Fig. 4 is a side elevation, partly broken away, of the emergency actuating mechanism. 30

Like letters refer to like parts throughout the several views.

In the accompanying drawings, I have shown at *a* an ordinary punch press, having 35 a ram *b* actuated from the power shaft *c* controllable by a clutch mechanism *d*. The trip mechanism for said clutch mechanism includes therein a pedal *e*. The bed of the press is at *f*. These characteristics are common to various types of presses to which a safety appliance made in accordance with 40 my invention may be applied.

Mounted toward the front of the bed *f* is a rock shaft *g* having parallel arms 45 *g'*—*g''* projected toward the punch or ram *b* and carrying a guard plate *g''* normally extending across and below the feeding space between the punch or ram and the operator. One end of the shaft *g* is provided 50 with a crank arm *g'* by means of which said plate *g''* receives a timely movement to force the hand or hands of the operator from beneath the punch or ram.

Each end of the shaft *g* serves as a trunnion for the plate *g''* and is mounted in a screw fitting *g'* adjustably mounted in a screw threaded socket in a fitting *g''* having a plate adapted to be screwed or bolted to the side of the bed *f*. By using fittings *g''*, 55 I avoid the necessity for drilling and tapping the bed and very much simplify the mounting of the guard plate.

The guard plate *g''* is adapted to be normally manually actuated simultaneously 60 with, and by the same mechanism used for

the tripping of the clutch mechanism *d*, supplemental automatically operative means being provided whereby the plate will be actuated from the power shaft *c* in the event of the clutch mechanism becoming 70 inoperative to arrest rotary movement of said shaft. Power for actuating the plate *g''* is transmitted through a single main actuating lever whether it be derived from the manually actuated mechanism, or 75 through the automatically operative mechanism. This main actuating lever has three diverging arms *h*—*i*— and *j* one of which as *i* preferably projects downwardly at substantially right angles to the other two. 80 Each of said arms has a forked end.

The arm *i* carries a pivotal block *i'* in which the screw threaded end of a link *i''* is fitted, the other end of said link being pivotally connected with the crank arm *g'*. 85 The arm *h* also carries a similar swivel, upon which one end of the clutch link *h'* is mounted, and through which the pedal link *h''* passes, said link being secured in any adjusted position by a set screw, or in any 90 other desired manner.

The arm *j* has pivotally connected therewith a link *j'*, the other end of which is pivotally connected with a cam lever *k* mounted in a bracket *k'* secured adjacent 95 the top of the press frame, and coöperating with a cam *k''* carried by the end of the shaft *c*, preferably adjacent the fly wheel.

By the foregoing construction, the main actuating lever may be similarly rocked by 100 means of either the connections between it and the lever *k* and cam *k''* constituting the emergency actuating mechanism, or between it and the foot pedal.

To avoid movement of the pedal *e* when 105 the plate *g* is actuated by the emergency actuating mechanism, I form the main actuating lever of two sections one of which comprises a hub *l* carrying the arms *i* and *j* and the diametrically opposite projections *m*—*m'* and the other of which comprises the hub *n* carrying the arm *h* and the diametrically opposite projections *o*—*o'*.

The projections *m* and *o* and *m'* and *o'* are arranged oppositely to each other, being 115 normally forced into engagement by the springs *p*—*p'* while being permitted to separate when power is applied to the arm *j* through the link *j'*. Preferably the contacting surfaces of opposite projections, extend 120 on planes slightly oblique to the axis of the hubs *l* and *n* so as to insure the various projections being restored to substantially the same position after each actuation through the link *j'* while permitting any 125 needed slight play during such actuation.

Both hubs *l* and *n* are mounted upon the pivot screw *q* by means of which the main actuating lever is mounted upon the press frame. 130

To prevent the manual movement of the plate imparting sufficient movement to the arm h to trip the clutch d , or to reverse the plate g^3 so as to make it inoperative; and to relieve the springs $p-p'$ from excessive stresses, I pivotally mount upon the projections $m'-o'$ a slotted plate r , which plate r will permit the desired automatic actuation of the main actuating mechanism, but will act as a positive stop to prevent any movement of the guard in excess of that required to raise the guard to the desired extent; and will not transmit movement to the arm h . Hence the operator cannot trip the clutch by raising the plate g^3 by hand.

To supplement the action of the plate r , I provide a link e pivoted to the press frame, and having a slotted end pivotally connected with the lever k which link will limit upward movement of the lever k , and thus act as a stop restricting the movement of the arm j to that required to properly set the plate g .

The operation of the herein described safety appliance is substantially as follows:

When a press is being actuated under normal conditions, that is by tripping the clutch d by means of the pedal e , each depression of said pedal will impart a downward stress upon the arm h through the link h' resulting in a downward thrust of the projection m and an upward thrust of the projection m' . The normal engagement of these projections with the projections $o-o'$ will impart rotative movement to the hub n and the arms $i-j$ carried thereby. The oscillation of the arms i will raise the plate g^3 with each actuation of the main actuating lever, but the arc described by said plate will be greater than that described by said arm i because of the relative variance in the radii at which the opposite ends of the link i^2 are operative as to said lever arm and the shaft g .

When the pedal e is depressed, the oscillation of the arm i will raise the lever k out of engagement with the cam k' and the downward movement of the arm h will, through the link h' trip the clutch d . The greater radius of the arm i relatively to the arms h and g^4 will insure the maximum throw being imparted to the plate g^3 before the ram b can descend to an extent to injure the hand of the operator, which will be forcibly removed from the feeding space between the ram and the operator, as the plate g^3 moves upwardly and toward said operator.

When the foot pedal is released, the spring acting thereon will restore the various parts to their normal position with the guard plate extending across and below the feeding space between the punch and the operator.

If for any reason, the shaft e should cease to be under the control of the clutch d , it

will rotate continuously. With each rotation of this shaft the single riser on the cam k^2 will raise the lever k and impart an upward stress upon the arm j and substantially the same oscillatory movement to the arm i as is normally imparted thereto by the arm h as heretofore described through the rotative movement imparted to the hub n . As said hub turns, it carries the projections $o-o'$ away from the projections $m-m'$ against the tension of the springs $p-p'$, without imparting movement to the arm h , or to the clutch d and pedal e connected therewith. As the lever k passes from the rise of the cam k^2 the springs $p-p'$ will restore the various parts to their normal positions.

It will be observed that when stresses are applied through the link h' to the arm h , all parts of the main actuating mechanism oscillate in unison but that when stresses are applied to said mechanism through the link j' or through the link i^2 , connected with the arms j and i respectively, no movement is imparted to the arm h or to either link connected therewith. As a result of this condition, the actuation of the plate g^3 by the cam k' will impart no such movement to the pedal e as could injure the operator, and no injury can result to the clutch mechanism. Furthermore, if an operator should endeavor to trip the press by raising the plate g^3 , which is a dangerous practice as well as one affecting the capacity of the press, the power transmitted through the link i^2 will merely oscillate the arms $i-j$ and will impart no movement to the arm h which must be oscillated to release the clutch.

The plate r and link s , or either or both of them, limit the oscillatory movement of the arm i acting as a positive stop when the plate g^3 has been raised to the desired extent to remove the hand of the operator from beneath the ram b . Hence, if the operator attempts to turn the plate g^3 so as to disengage the lever k from the cam k' , and have the plate project from the shaft g toward him, thus making the appliance inoperative, the limit stop mechanism above referred to will prevent such a movement of the plate.

It is not my intention to limit the invention to the details of construction shown in the accompanying drawings, it being apparent that such may be varied without departing from the spirit and scope of the invention.

Having described the invention, what I claim as new and desire to have protected by Letters Patent is:—

1. A safety appliance for hand fed power presses embodying therein a guard plate normally extending across and below the feeding space between the ram and the operator and actuating means therefor comprising

ing a main actuating lever having three diverging arms, an emergency actuating mechanism consisting of a cam carried by the power shaft of a press, and a cam lever co-
5 operating therewith, and connections between one arm of said main actuating lever and said cam lever, between another arm of said main actuating lever and the clutch tripping mechanism of a press and between
10 the remaining arm of said main actuating lever and said guard plate.

2. A safety appliance for hand fed power presses embodying therein an oscillatory guard plate normally extending across and
15 below the feeding space between the ram and the operator and actuating means therefor comprising a main actuating lever having three diverging arms, an emergency actuating mechanism consisting of a cam carried
20 by the power shaft of a press, and a cam lever coöperating therewith, and connections between one arm of said main actuating lever and said cam lever, between another arm of said main actuating lever and the
25 clutch tripping mechanism of a press and between the remaining arm of said main actuating lever and said guard plate whereby said plate will be moved upwardly and toward the operator with each actuation of
30 said main actuating mechanism.

3. A safety appliance for hand fed power presses embodying therein a guard plate normally extending across and below the feeding space between the ram and the operator, and actuating means therefor, comprising a main actuating lever having three diverging arms, an emergency actuating mechanism consisting of a cam carried by the power shaft of a press, and a cam lever co-
40 operating therewith, and connections between one arm of said main actuating lever and said cam lever, between another arm of said main actuating lever and the clutch tripping mechanism of a press, and between
45 the remaining arm of said main actuating lever and said guard plate, the arm connected with said lever and the arm connected with said guard plate being operatively connected, and movable independently of, or
50 simultaneously with, said arm connected with the clutch tripping mechanism, whereby said guard plate may be actuated by said cam lever without imparting movement to, and the manual movement of said plate can-
55 not actuate, said clutch tripping mechanism.

4. A safety appliance for hand fed power presses embodying therein a guard plate normally extending across and below the feeding space between the ram and the operator, and actuating means therefor comprising a main actuating lever having three diverging arms, an emergency actuating mechanism consisting of a cam carried by the power shaft of a press, and a cam lever co-

operating therewith, and connections be- 65 tween one arm of said main actuating lever and said cam lever, between another arm of said main actuating lever and the clutch tripping mechanism of a press, and between the remaining arm of said main actuating 70 lever and said guard plate, the arm connected with said lever and the arm connected with said guard plate being operatively connected, and movable independently of, or simultaneously with, said arm connected 75 with the clutch tripping mechanism, whereby said guard plate may be actuated by said cam lever without imparting movement to, and the manual movement of said plate can- 80 not actuate, said clutch tripping mechanism, and means limiting the extent of such independent movement to prevent the appliance being made inoperative by excessive movement of the guard plate.

5. A safety appliance for hand fed power 85 presses embodying therein a guard plate normally extending across and below the feeding space between the ram and the operator, and actuating means therefor comprising a main actuating mechanism consist- 90 ing of a bearing having mounted thereon two hubs, one of said hubs having thereon a projection and angularly extending arms, and the other of said hubs having thereon a projection oppositely disposed to the pro- 95 jection on said first named hub, and a single arm, a spring mechanism whereby said pro- jections are normally held in engagement, but are permitted to separate, an emergency 100 actuating mechanism consisting of a cam carried by the power shaft of a press, and a cam lever coöperating therewith, connections between one of the arms on said first named hub and said guard plate, and the other arm on said hub and said cam lever, and connections between the arm on said other hub and the clutch tripping mechanism of a press.

6. A safety appliance for hand fed power 110 presses embodying therein a guard plate normally extending across and below the feeding space between the ram and the operator, and actuating means therefor comprising a main actuating mechanism consisting of a bearing having mounted thereon two hubs, one of 115 said hubs having thereon a projection and angularly extending arms, and the other of said hubs having thereon a projection oppositely disposed to the projection on said first named hub, and a single arm, a spring mechanism whereby said projections are normally held in engagement, but are permitted to separate, an emergency actuating mechanism 120 consisting of a cam carried by the power shaft of a press, a cam lever coöperating therewith, connections between one of the 125 arms on said first named hub and said guard plate, and the other arm on said hub and said cam lever, and connections between the

- arm on said other hub and the clutch tripping mechanism of a press, and a stop mechanism whereby movement of said first named hub and the arms carried thereby with relation to said other hub and the arm carried thereby is limited to that necessary to actuate said guard plate. 65
- 5 70
7. A safety appliance for hand fed power presses embodying therein a guard plate normally extending across and below the feeding space between the ram and the operator, and actuating means therefor comprising a main actuating mechanism consisting of a bearing having mounted thereon two hubs, one of said hubs having thereon a plurality of substantially diametrically oppositely disposed projections and angularly extending arms and the other of said hubs having thereon a plurality of substantially 75
- 10 diametrically oppositely disposed projections oppositely disposed to the projections on said first named hub respectively and adapted to operatively engage same, and a single arm, a spring acting upon each projection upon each hub and upon the projection upon the other hub coöperating therewith whereby said projections are normally held in engagement with each other but are 80
- 15 permitted to separate, an emergency actuating mechanism consisting of a cam carried by the power shaft of a press, and a cam lever coöperating therewith, connections between one of the arms on said first named hub and said guard plate, and the other arm 85
- 20 on said hub and said cam lever, connections between the arm on said other hub and the clutch tripping mechanism of a press, and a slotted link pivotally connected with the frame of a press and with said cam lever 90
- 25 whereby the movement of said guard plate is limited. 95
- 30 100
8. A safety appliance for hand fed power presses embodying therein a guard plate normally extending across and below the feeding space between the ram and the operator, and actuating means therefor comprising a main actuating mechanism consisting of a bearing having mounted thereon two hubs, one of said hubs having thereon a plurality of substantially diametrically oppositely disposed projections and angularly extending arms and the other of said hubs having thereon a plurality of substantially 105
- 35 diametrically oppositely disposed projections oppositely disposed to the projections on said first named hub respectively and adapted to operatively engage same, and a single arm, a spring acting upon each projection upon each hub and upon the projection upon the other hub coöperating therewith whereby said projections are normally held in engagement with each other but are 110
- 40 permitted to separate, an emergency actuating mechanism consisting of a cam carried by the power shaft of a press, and a cam lever coöperating therewith, connections between one of the arms on said first named hub and said guard plate, and the other arm 115
- 45 on said hub and said cam lever, and connections between the arm on said other hub and the clutch tripping mechanism of a press. 120
- 50 125
9. A safety appliance for hand fed power presses embodying therein a guard plate normally extending across and below the feeding space between the ram and the operator, and actuating means therefor comprising a main actuating mechanism consisting of a bearing having mounted thereon two hubs, one of said hubs having thereon a projection and angularly extending arms, and the other of said hubs having thereon a projection oppositely disposed to the projection on said first named hub, and a single arm, a spring mechanism whereby said projections are normally held in engagement, but are permitted to separate, an emergency actuating mechanism consisting of a cam carried by the power shaft of a press, and a cam lever coöperating therewith, connections between one of the arms on said first named hub and said guard plate, and the other arm on said hub and said cam lever, connections between the arm on said other hub and the clutch tripping mechanism of a press, and a slotted link pivotally connected with the frame of a press and with said cam lever whereby the movement of said guard plate is limited. 90
- 55 95
10. A safety appliance for hand fed power presses embodying therein a guard plate normally extending across and below the feeding space between the ram and the operator, and actuating means therefor comprising a main actuating mechanism consisting of a bearing having mounted thereon two hubs, one of said hubs having thereon a plurality of substantially diametrically oppositely disposed projections and angularly extending arms and the other of said hubs having thereon a plurality of substantially diametrically oppositely disposed projections oppositely disposed to the projections on said first named hub respectively and adapted to operatively engage same, and a single arm, a spring acting upon each projection upon each hub and upon the projection upon the other hub coöperating therewith whereby said projections are normally held in engagement with each other but are 100
- 60 permitted to separate, an emergency actuating mechanism consisting of a cam carried by the power shaft of a press, and a cam lever coöperating therewith, connections between one of the arms on said first named hub and said guard plate, and the other arm on said hub and said cam lever, connections between the arm on said other hub and the clutch tripping mechanism of a press, a slotted link pivotally connected with one of

the projections upon each hub whereby the extent of separation of said projections is limited, and a slotted link pivotally connected with a press frame and with said cam 5 lever whereby the action of said first named slot in limiting the separation of said projection is supplemented.

In witness whereof I have hereunto affixed

my signature in the presence of two subscribing witnesses, this 28th day of August, 1916.
